LAWN SPRINKLER

Russell B. Nelson, Peoria, and Robert K. Unter, Roscoe, Ill., assignors to L. R. Nelson Mfg. Co., Inc., Peoria,
Ill., a corporation of Illinois

Filed Aug. 16, 1962, Ser. No. 71,332

Term of patent 14 years

(Cl. D91—1)

Fig. 1.

Fig. 2.

The dominant features of our new design are shown in solid lines.

We claim:

The ornamental design for a lawn sprinkler, as shown and described.
